A. SUNDH.
FLUID MOTOR OR PUMP.
APPLICATION FILED MAR. 21, 1914.

Patented June 6, 1916.

UNITED STATES PATENT OFFICE.

AUGUST SUNDH, OF HASTINGS-UPON-HUDSON, NEW YORK, ASSIGNOR TO OTIS
ELEVATOR COMPANY, A CORPORATION OF NEW JERSEY.

FLUID MOTOR OR PUMP.

1,185,955.

Specification of Letters Patent.

Patented June 6, 1916.

Application filed March 21, 1914. Serial No. 826,168.

To all whom it may concern:

Be it known that I, AUGUST SUNDH, a citizen of the United States, residing at Hastings-upon-Hudson, in the county of Westchester and State of New York, have invented a new and useful Improvement in Fluid Motors or Pumps, of which the following is a specification.

My invention relates to fluid motors or pumps and is particularly directed to a motor or pump in which there are a plurality of oscillating cylinders arranged in a vertical plane and radially disposed about a common crank shaft.

15 The principal object of the invention is the provision of simple, practical and efficient means for balancing the weight of moving parts and for balancing the action of fluid pressure thereon.

20 Other objects of the invention will appear hereinafter, the novel combinations of elements being pointed out in the annexed claims.

In the drawings, Figure 1 is a view in 25 sectional elevation of a motor or pump containing an embodiment of the invention; Fig. 2 is a side sectional view of the same; Fig. 3 represents one of the oscillating cylinders as viewed from the open end of the 30 cylinder bore.

Like reference numerals designate similar parts in all of the figures.

The pump or motor herein shown is substantially like that disclosed in my co-pending application, Ser. No. 764,994, filed May 2, 1913, for "power transmission devices," therefore a detail description of the same will not be necessary.

Referring to the drawing, I show a plurality of oscillating cylinders such as 1, 2, 3, 4 and 5, which are substantially similar to each other and each comprises a circular disk which is bored through the center at right angles to the axis of the disk, so as to 45 form a cylinder bore. Within each cylinder bore is a plunger or trunk piston, such as 6, 7, 8, 9 and 10, and these pistons are operatively connected to a single throw balanced crank shaft 11. Each cylinder, such 50 as the cylinder 1, is snugly surrounded throughout the greater part of its periphery by a bushing 12 which is fixed against movement in a circular bore formed in the pump

or motor casting 13. At diametrically opposite points in the periphery of each cylinder are arranged ports 14 and 15 which lead into the cylinder and are adapted alternately to register with stationary ports 16 and 17 in the bushing 12, which are in communication with corresponding pressure 60 and discharge chambers 19 and 20, respectively, formed in the head 21. This head is bolted to the pump or motor casting 1 and a fluid tight joint between the two is secured by means of the concentric packings 22, 22, 65 which are retained in corresponding grooves in the casting 13. The several pistons 6, 7, 8, 9 and 10 are preferably cored out so as to reduce their weight to a minimum and thereby permit of high speeds, while the inner end of each piston is slotted at 23 (see Fig. 2) so as to permit the piston to extend almost to the end of the cylinder bore at the inner end of its stroke without restricting the entrance or exit of fluid to and from the 75 cylinder by way of the ports 14 and 15.

The operation of the device as a fluid motor may be described as follows: Assuming that the chamber 19 is piped to a suitable source of fluid pressure, fluid will enter the 80 cylinders 2 and 3 and drive the crank shaft in an anti-clockwise direction, the cylinder 1 being on dead center, while the cylinders 4 and 5 are open to the exhaust chamber 20. As the crank shaft rotates the angular position of the pistons is varied, causing the cylinders to oscillate and thereby automatically 85 control the entrance and exit of fluid between each cylinder and the pressure and exhaust chambers 19 and 20, respectively, 90 and the crank shaft rotates continuously.

In a device of the character just described, it will be observed that at times the cylinders are subjected to an unbalanced fluid pressure tending to force the cylinders 95 against their respective bushings. Then again, the unbalanced weight of the cylinders themselves is sustained by the bushings. In both cases more pressure is brought to bear on one portion of the bushings than 100 on another portion, and the obvious result is that the cylinders or bushings, or both, wear unevenly, and, after the device has been in operation for some time, its efficiency becomes considerably less, due to 105 leaks which have developed. Furthermore,

this unbalanced condition of parts tends to set up excessive friction which tends further to reduce the efficiency of the device.

In order to overcome the above noted 5 disadvantageous features and to obtain a substantial balance of the cylinders, I resort to the following expedient: Considering first the upper cylinder 1, it will be seen that the full diameter of the cylinder bore 10 does not extend completely through the cylinder, but only to within a short distance of the upper end so as to leave a pair of projections 24, 24, integral with the cylinder. Upon admitting fluid pressure to this cylinder 15 the pressure will act against the lower part of the projections 24, 24, tending bodily to move the cylinder upwardly in accordance with the amount of pressure and the effective area of the projections which are 20 exposed to this pressure. Thus, by properly proportioning the effective area of these projections, the weight of the cylinder may be accurately balanced so that the latter will "float" in the bushing 12 25 rounding it and all wear and friction between the cylinder and bushing eliminated. The cylinders 2 and 5 are provided with projections 25 and 26, respectively, which are similar in every respect to the projections 30 of the cylinder 1, excepting that they have a less effective area for the pressure to act upon. Whereas the action of fluid pressure upon the projections 25 and 26 of cylinders 2 and 5, respectively, does 35 not act in a vertical direction, it does act in a direction tending to compensate for the weight of these cylinders. The bore of the cylinders 3 and 4 extends completely through the cylinders and no projections 40 are provided for these cylinders, as in the case of the cylinders 1, 2 and 5. In order to balance the weight of these cylinders I provide for the cylinder 4 a recess or circular counterbore 28 adjacent the corresponding cylinder bushing, and this counterbore 45 is formed eccentric to the cylinder bore in which the piston operates as shown in Fig. 3. As fluid under pressure is admitted to the cylinder 4, the pressure in the counterbore 50 55 60 65 70 75 80 85 90 95 100 105 110 115 120 125 130 135 140 145 150 155 160 165 170 175 180 185 190 195 200 port 16 is open to the cylinder port 14 and fluid pressure is not directed from the port 16 to the periphery of the cylinder. The recess 31 of this cylinder is controlled by the 5 duct 33 in precisely the same manner as the duct 34 controls the entrance of fluid pressure to the recess 32, so that any pressure upon the periphery of the cylinder 1 due to a fluid pressure at the port 17 in the bushing is exactly balanced by an equal and opposite pressure in the recess 31.

The arrangement of recesses and ducts in the remaining cylinders 2, 3, 4 and 5, is similar to that just described in connection with 15 the cylinder 1. In these remaining cylinders, however, the area of the recess in each bushing lying below a horizontal line drawn through the center of the corresponding cylinder is made somewhat greater than that necessary exactly to balance the port pressure. By reason of this arrangement, the 20 port pressure opposite these enlarged recesses is overbalanced, or in other words the fluid pressure is utilized partially to support or counteract the weight of the cylinders themselves. For example, consider the cylinder 5 of Fig. 1: The lower recess 35 is 25 purposely made of greater area than that of the port 36, so that the upward pressure exerted on the cylinder at the recess 35 is enough greater than the opposing pressure of fluid acting downwardly on the cylinder at the port 36 to balance a portion of the weight of the cylinder as well as to balance 30 the downward pressure at the port 36. Whereas it would be possible to proportion the area of the recess 35 so as to balance the entire weight of the cylinder, I prefer to leave a portion of this weight unbalanced as 35 far as the pressure in the recess 35 is concerned and to permit this unbalanced weight to be taken care of by the action of fluid upon the projections 26 formed at the inner end of the cylinder bore. The total lifting 40 force upon the cylinder will be the resultant of the forces acting at the recess 35 and projections 26.

By reason of my invention, it becomes 45 possible to effect a substantially balanced condition of parts in a fluid motor or pump which permits the same to operate with a high degree of efficiency and at high speeds without vibration and with negligible friction losses. While I have disclosed my 50 invention in connection with a fluid motor or pump having five single acting oscillating cylinders radially disposed about a common crank shaft, it is obvious that the invention is equally well adapted to other types of 55 pumps or motors or other devices wherein it is desirable to effect a balance of the parts by means of fluid pressure. For this reason, I desire not to be limited to the precise arrangement and construction of parts herein 60 disclosed.

What I claim is:—

1. In a fluid motor or pump, the combination of a plurality of radially disposed oscillating cylinders, pistons in the cylinders, and means for balancing the weight of said 70 cylinders.

2. In a fluid motor or pump, the combination of a plurality of radially disposed oscillating cylinders, pistons in the cylinders, and means for balancing the action of fluid pressure 75 and of gravity on said cylinders.

3. In a fluid motor or pump, the combination of a plurality of radially disposed oscillating cylinders, pistons in the cylinders, and fluid pressure means for balancing the action 80 of fluid pressure and gravity on said cylinders.

4. In a fluid motor or pump, the combination of a crank shaft, a plurality of oscillating disks radially disposed about said shaft, cylinders formed in said disks, pistons in the cylinders connected to said crank shaft, means for directing fluid to said pistons and means for alternately directing fluid to the periphery of said oscillating 90 disks to compensate for the action of fluid pressure and gravity on said disks.

5. In a fluid motor or pump, the combination of a plurality of oscillating cylinders arranged in a vertical plane and radially disposed about a common crank shaft, and means for directing a pressure in the proper direction against said cylinders to balance the same against material weights and 95 against fluid pressure.

6. In a fluid motor or pump, the combination of a plurality of oscillating cylinders arranged in a vertical plane and radially disposed about a common crank shaft, and fluid means for directing a pressure in the proper direction against said cylinders to balance the same against material weights and 105 against fluid pressure.

7. In a fluid motor or pump, the combination of a plurality of oscillating cylinders arranged in a vertical plane and radially disposed about a common crank shaft, and means for balancing said cylinders against fluid pressure and the action of gravity in accordance with the position of the cylinders 110 in relation to a common center.

8. In a fluid motor or pump, the combination of a plurality of cylinders comprising oscillating disks radially disposed about a common crank shaft, pistons in the cylinders connected to the crank shaft, ports for directing fluid to the pistons, and additional ports for directing fluid pressure against the cylinders to balance the same against pressure and the action of gravity.

9. In a fluid motor or pump, the combination of a casting, a plurality of cylinders therein, said cylinders comprising rocking or oscillating disks radially disposed about a common crank shaft, a cover for one end of 130

the casting, annular fluid chambers in said cover, means for directing fluid between said cylinders and chambers, and annular grooves in said casting adapted to receive packing 5 and thereby form a fluid tight joint between the casting and cover and between the annular chambers.

In testimony whereof, I have signed my name to this specification in the presence of two subscribing witnesses.

AUGUST SUNDH.
